[57] CLAIM

The ornamental design for a shotshell carrier, as shown and described.

DESCRIPTION

FIG. 1 is a perspective view of a shotshell carrier showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof; and,

FIG. 7 is a rear elevational view thereof.

The cross-hatched shading variations are used to show contrasting surface materials.

FIG. 1

FIG. 2
